Primary Examiner — Lauren R Calve(74) *Attorney, Agent, or Firm* — Eric Karich; Karich & Associates(57) **CLAIM**

The ornamental design for a knife holder, as shown and described.

DESCRIPTION

FIG. 1 is a front perspective view of a knife holder, showing my new design in a closed configuration;

FIG. 2 is a rear perspective view thereof;

FIG. 3 is a sectional view thereof taken along line 3-3 in FIG. 1;

FIG. 4 is a front perspective view of the knife holder in a display configuration;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

1 Claim, 3 Drawing Sheets(56)
